UNITED STATES PATENT OFFICE.

JOSEPH W. FRY, OF CLEVELAND, OHIO, ASSIGNOR OF ONE-HALF TO
MONROE TINKEY, OF SAME PLACE.

AUTOMATIC FLUSHING MECHANISM.

SPECIFICATION forming part of Letters Patent No. 621,058, dated March 14, 1899.

Application filed September 20, 1898. Serial No. 691,436. (No model.)

To all whom it may concern:

Be it known that I, JOSEPH W. FRY, a citizen of the United States, residing at Cleveland, in the county of Cuyahoga and State of Ohio, have invented certain new and useful Improvements in Automatic Flushing Mechanism; and I do declare that the following is a full, clear, and exact description of the invention, which will enable others skilled in the art to which it appertains to make and use the same.

My invention relates to improvements in automatic flushing mechanism for water-closets; and the improvement consists in the peculiar construction and novel combination of parts, substantially as hereinafter described, and more particularly pointed out in the claims.

The object of the invention is to provide a water-closet bowl with an automatic arrangement which will fill the flushing-tank with water when the seat is occupied, and discharge the water with sufficient force to flush the bowl when vacated.

25 In the accompanying drawing the single figure is a side elevation of a bowl with the flushing-tank and valve mechanism shown in section.

The bowl 2 is of any desired form or construction, but preferably of the kind which has a hinged seat-cover 3 at its top. At the back of this bowl and also resting on the top thereof is the flushing-tank 4, which has its outlet 5 connected directly with the flushing-35 rim of the bowl. The water-supply pipe 6 leads from the bottom of the tank 4 down to and beneath the floor to a governing-valve 7, centrally located at the front and also beneath the floor. This valve 7 could be placed above 40 but is preferably arranged below the floor to avoid exposure to the elements, especially where the bowl is placed in an outhouse or the like, where freezing is likely to occur. The governing-valve 7 is provided with a supply-chamber 8 and a waste-chamber 9, and these 45 chambers are divided by a wall 10, which has valve-seats in each side of its face, and the chambers are connected by an open passage 11, leading from seat to seat. A stem 12 50 passes centrally through the passage and out through a bushing at the top of the valve 7

and extends up and against the bottom and outer end of the seat-cover 3. Valves 13 and 14 on the stem 12 are arranged within the chambers 8 and 9, and when one of the said 55 valves is on its seat the other is off and open. The main supply pipe and inlet to the governing-valve 7 is located directly opposite the bottom face of the valve 13, and because of this arrangement the force of the water comes 60 full against the said face of valve 13 and serves to keep the same normally closed and the water-supply cut off from the flushing-tank 4. It also keeps the seat 3, by means of stem 12, in raised position, about as seen in 65 full lines of the illustration. When the valve 13 is thus closed, the valve 14 is open and chamber 9 becomes the waste-chamber, through which the waste water in the local supply-pipe 6 is drawn off through the waste-pipe 15, 70 leading from chamber 9 to the main outflow 16'. As soon and as long as the seat 3 is occupied the stem 12 is depressed, valve 13 is open, and valve 14 closed. The waste-passage is thus cut off, and the water is free to enter 75 supply-pipe 6 and pass to the flushing-tank 4, where it first enters a piston-chamber 16 before discharging into the tank proper. The water enters the bottom end of the piston-chamber, and the force of the same comes 80 head on against the end of the piston-valve 17 and carries the piston up and beyond openings 18, through which the water then discharges into tank 4. The pressure of the water keeps the piston up in raised position 85 and is utilized to close the flush-valve 19 and keep it closed until it is released, as herein-after described. In the meantime the tank fills to its limit, which limit is controlled by an air-valve 18' and float 19'. As the water 90 rises the float is carried up until air-valve 18' is closed. The water will continue to rise under its own pressure and compress the air within the top of the now air-tight tank, and the forced water-level obtained is maintained 95 until the occupant vacates the seat 3 and the pressure upon valve 13 closes the said valve and cuts off the water-pressure on the piston-valve 17 and allows the flush-pipe valve to be opened. The water will then flow rapidly and 100 with force out of outlet 5 and flush the bowl. The operative connection between piston-

valve 17 and valve 19 consists of a link 20, pivotally connected to the apex of the conceal hinged valve 19 and to the end of the piston-stem 21. A spring 22, within the piston-chamber 16, bears on the piston, and when the water is cut off forces piston-valve 17 down and opens valve 19, as seen in full lines. The back of the valve is cone-shaped, as described, to decrease the amount of resistance in opening the same occasioned by the weight and pressure of the water in the tank. This form of valve allows a quicker action with less pressure of water against the piston to operate the said parts.

15 The advantages of a flushing mechanism constructed and arranged as described are as follows: The closet whenever used is sure to be automatically flushed without the attention or care of the occupant, the tank and exposed pipes are free from water at all times except when the seat is occupied, preventing freezing or chance of leakage, and the construction as a whole is so simple and compact that it is both convenient and durable, 25 as well as efficient in operation.

What I claim as new, and desire to secure by Letters Patent, is—

1. In water-closets, a flush-tank and an outlet-valve therefor, a water-inlet chamber 30 for said tank, and a supply-pipe thereto, a valve in said inlet-chamber constructed to be raised by water-pressure to establish flow of water to the tank, and a spring to restore the inlet-valve to its seat when the supply-pressure is cut off, and connections between said outlet-valve for the tank and the inlet-valve for the said chamber, substantially as described.

2. The combination of the closet-bowl and 40 seat and the flush-tank and inlet-chamber therefor, a water-supply pipe to said chamber and a valve to close said water-supply having operating connection with the said seat, and connected inlet and outlet valves 45 for the flush-tank, substantially as described.

3. Flushing mechanism for water-closets comprising the bowl and seat, a flushing-tank, a water-supply-governing valve and a stem therefor, said valve arranged to be closed by 50 water-pressure, in combination with an out-

let-valve within the flushing-tank and an inlet-valve connected therewith, substantially as described.

4. Flushing mechanism for water-closets comprising a water-supply pipe leading to the 55 flushing-tank and a governing-valve therefor constructed and arranged to be kept closed by the water-pressure, in combination with a flushing-tank and an outlet-valve therefor, an inlet-chamber for said tank and a valve 60 therein, and pivoted connections between said valves, substantially as described.

5. The bowl and the seat thereon, flushing mechanism comprising a flushing-tank, a water-supply-governing valve and a rod therefor extending to the seat, said valve arranged to be kept closed by the pressure of the water, a piston-valve chamber within the flushing-tank, a supply-pipe leading from said chamber to said governing-valve, a spring-pressed 65 piston-valve within said chamber, a flushing-valve hinged and seated at the outlet of said tank, a link connection between said piston-valve and flushing-valve, and an air-valve in the top of said tank, all said parts combined 70 and operating, substantially as described.

6. A closet-bowl and a flushing-tank mounted thereon, a hinged seat for said bowl, a set of water-supply and waste chambers, valves within said chambers and a stem connecting 80 said valves and arranged to engage the said hinged seat and be depressed thereby, the valve within the supply-chamber being seated opposite the water-inlet and constructed to be kept closed by water-pressure from the 85 main, in combination with valve mechanism within the flushing-tank comprising a conical-shaped flush-valve and a float-controlled air-valve, and a chamber and piston-valve in said chamber, and a link and pivoted arm 90 connecting said piston-valve and the said flush-valve and a spring to close the piston-valve and open the flush-valve in the same action, substantially as described.

Witness my hand to the foregoing specification this 3d day of September, 1898.

JOSEPH W. FRY.
